UNITED STATES PATENT OFFICE.

EDWARD J. PAQUE, OF CINCINNATI, OHIO, ASSIGNOR TO THE POLLAK STEEL COMPANY, OF CINCINNATI, OHIO, A CORPORATION OF OHIO.

MACHINE FOR FORGING ARTICLES FROM METAL BLANKS.

1,386,726.

Specification of Letters Patent.

Patented Aug. 9, 1921.

Application filed November 17, 1919. Serial No. 338,579.

To all whom it may concern:

Be it known that I, EDWARD J. PAQUE, a citizen of the United States of America, and a resident of Cincinnati, in the county 5 of Hamilton and State of Ohio, have invented a new and useful Improvement in Machines for Forging Articles from Metal Blanks, of which the following is a specification.

10 The object of my invention is a machine having means for automatically centering a blank upon one member of the die, of automatically stripping the article from the die and of ejecting the article from the die.

15 These and other objects are attained by the means described in the specification and illustrated in the accompanying drawings, in which:—

Figure 1, is a perspective view of a press 20 embodying my invention, part of one of the guide posts being broken away to expose the parts of the forge in the rear thereof.

Fig. 2, is a detail view partly in section and partly in side elevation of the mold 25 members.

Figs. 3 and 4, are sectional views of the steel blank and of the articles such as blank forgings from which bevel gears can be machined, respectively.

30 Referring to the parts:

The machine embodying my invention comprises a die having a female member A, a male member B, a reciprocating head D, which reciprocates upon guide posts d, and 35 is moved, preferably by hydraulic pressure to carry the male member downward to compress the metal blank which has been placed within the female member of the die.

The female member has a central recess a, 40 below which is a central axial bore a' and a transverse bore a''. In the bottom of recess a is seated the head e of an ejector whose stem e' extends through the bore a' within which it is retained by a pin e² which 45 is fixed in the side walls of the bore a' and projects through a longitudinal slot e³ in the stem e'. Within the transverse bore a'' is mounted a lever e⁴ whose end projects beneath the end of the stem e'.

50 Male member B has a central internal screw-threaded recess b into which is screwed

the stem of a boss b' which has a tapered end b² which forms the inner walls of the die chamber, when the die members have been brought into contact. This tapered 55 end b² performs also the function of centering the ring blank within the recess a.

A ring member F is mounted reciprocally upon the male die, and surrounds the boss b', by means of bars H which have 60 slots h for engaging the shanks of pins h', which are secured in the sides of the male member B. The bars H are secured to the ring member F by means of pins f. Mounted pivotally upon each side of the female 65 member A are retainer members which comprise arms k, which are pivoted to the sides of the female member, and carry retainer rods K which are adapted to engage the upper faces of the ring F after the die members have been brought into contact with each other. 70

In operation an annular ring blank, which is to be changed from the form shown in Fig. 3, to the form shown in Fig. 4, is placed 75 within the recess a upon top of the ejector, the retainers being placed in the position shown in Fig. 1. Then the head D is lowered, the tapered end of the boss enters the ring blank and centers it within the recess. 80 Upon completion of the stroke of the head D, the metal of the ring blank is compressed between the walls formed by the recess a, ring member F, the tapered end b² of the 85 boss and the ejector e.

Then rods K are engaged with the upper face of the ring F and the head D is raised. Thereby the article is stripped from the boss, then the retainers are thrown to one side and the lever e⁴ is actuated so as to 90 cause the ejector e to push the article from the die.

Having thus described my invention, what I claim is:—

In a machine of the character described 95 the combination of a female die having a recess in its upper face, an ejector plate seated removably upon the bottom of the die, a male die having a boss of smaller diameter than the recess and adapted to move 100 in axial alinement with the recess and having a tapered end adapted to enter the re-

cess and to form the inner walls of a die chamber, a ring member, means for mounting the ring member reciprocally around the boss so that the lower face of the ring member forms the upper walls of the die in the closed position of the dies, a retainer carried by the female die and adapted to be

engaged with the ring member upon the return movement of the male die and means adapted to actuate the ejector.

10

In testimony whereof, I have subscribed my name this 12th day of November, 1919.

EDWARD J. PAQUE.
